UNITED STATES PATENT OFFICE

157,440

AIRPLANE CONTROL WHEEL

Cornelius M. Schindler, Hagerstown, Md., assignor
to Fairchild Engine & Airplane Corporation, a
corporation of Maryland

Application October 5, 1948, Serial No. 148,972

Term of patent 14 years

(Cl. D14—30)

To all whom it may concern:

Be it known that I, Cornelius M. Schindler, a citizen of the United States of America, residing in the city of Hagerstown, in the county of Washington and State of Maryland, have invented a new, original, and ornamental Design for an Airplane Control Wheel, of which the following is a specification, reference being had to the accompanying drawing, forming a part thereof.

Fig. 1 is a top plan view of the airplane control wheel embodying the new design;

Fig. 2 is a front elevational view, and

Fig. 3 is a side elevational view thereof.

I claim:

The ornamental design for an airplane control wheel, substantially as shown.

CORNELIUS M. SCHINDLER.
